UNITED STATES PATENT OFFICE

99,221

DESIGN FOR A TOWEL DISPENSING CABINET

Frank G. Steiner, Chicago, Ill., assignor to Steiner Sales Company, Chicago, Ill., a corporation of Utah

Application February 7, 1936, Serial No. 61,027

Term of patent 14 years

To all whom it may concern:

Be it known that I, Frank G. Steiner, a citizen of the United States, residing at Chicago, in the county of Cook and State of Illinois, have invented a new, original, and ornamental Design for a Towel Dispensing Cabinet, of which the following is a specification, reference being had to the accompanying drawing, forming part thereof.

The figure is a perspective view of a towel dispensing cabinet embodying my design.

I claim:

The ornamental design for a towel dispensing cabinet as shown.

FRANK G. STEINER.
